(57) **CLAIM**

The ornamental design for a suspension perfume diffuser, as shown and described.

DESCRIPTION

FIG. 1 is a top, rear and right side perspective view of a suspension perfume diffuser showing my new design;
FIG. 2 is a bottom, front and left side perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is an enlarged view of portion 9 in FIG. 4.
The dash-dot-dash broken lines define the boundary of an enlarged view and form no part of the claimed design.
